FROZEN CARBONATED BEVERAGE MACHINE

William A. Gran, Independence, Mo., assignor to The
Vendo Company, Kansas City, Mo.

Filed Sept. 12, 1969, Ser. No. 19,131

Term of patent 14 years

Int. Cl. D15—12

U.S. Cl. D94—3

Fig. 1.

Fig. 2.

Fig. 3.

Fig. 4.

Fig. 5.

FIG. 1 is a side elevational view of the frozen carbonated beverage machine, showing my new design;

FIG. 2 is a front elevational view thereof;

FIG. 3 is a rear elevational view thereof;

FIG. 4 is a side elevational view of the opposite side shown in FIG. 1, with the splash guard in a lowered position; and

FIG. 5 is a front elevational view with the splash guard in a lowered position.

I claim:

The ornamental design for a frozen carbonated beverage machine, as shown and described.
